UNITED STATES PATENT OFFICE

132,817

DESIGN FOR A HAIR RETAINER FOR DRY SHAVERS

Jan Streng, Mason, N. H., assignor to Remington
Rand Inc., Buffalo, N. Y., a corporation of Delaware

Application January 9, 1942, Serial No. 105,087

Term of patent 14 years

To all whom it may concern:

Be it known that I, Jan Streng, a citizen of the United States, residing at Mason, in the county of Hillsboro and State of New Hampshire, have invented a new, original, and ornamental Design for a Hair Retainer for Dry Shavers, of which the following is a specification, reference being had to the accompanying drawing forming part thereof.

Fig. 1 is a side elevational view of the hair retainer for dry shavers showing my new design.

Fig. 2 is an end elevational view.

Fig. 3 is a top plan view, and

Fig. 4 is a cross sectional view taken on line 4—4 of Fig. 1 showing the inner face of an end member of the hair retainer in elevation.

I claim:

The ornamental design for a hair retainer for dry shavers, as shown.

JAN STRENG.
